Primary Examiner — Marissa J Cash(74) *Attorney, Agent, or Firm* — Timmer Law Group, PLLC(57) **CLAIM**

The ornamental design for an aircraft, as shown and described.

DESCRIPTION

FIG. 1 is a top, right front perspective view of an aircraft with the rotor nacelles facing forward;
FIG. 2 is a front elevational view of FIG. 1;
FIG. 3 is a right side elevational view of FIG. 1;
FIG. 4 is a left side elevational view of FIG. 1;
FIG. 5 is a top plan view of FIG. 1;
FIG. 6 is a bottom plan view of FIG. 1;
FIG. 7 is a top, right front perspective view of the aircraft with the rotor nacelles facing upward;
FIG. 8 is a front elevational view of FIG. 7;
FIG. 9 is a right side elevational view of FIG. 7;
FIG. 10 is a left side elevational view of FIG. 7;
FIG. 11 is a top plan view of FIG. 7; and,
FIG. 12 is a bottom plan view of FIG. 7.
The broken lines in the drawings illustrate portions of the aircraft that form no part of the claimed design.
